UNITED STATES PATENT OFFICE.

CHARLES W. WITHENBURY, OF CINCINNATI, OHIO.

GRATE-BAR.

SPECIFICATION forming part of Letters Patent No. 236,924, dated January 25, 1881.

Application filed December 3, 1880. (No model.)

To all whom it may concern:

Be it known that I, CHARLES W. WITHENBURY, of Cincinnati, in the county of Hamilton and State of Ohio, have invented certain 5 new and useful Improvements in Grate-Bars, of which the following is a specification.

My invention is in the nature of an improvement upon grate-bars for furnaces, and relates more especially to grate-bars which are cast 10 singly in short lengths, and has for its object the construction of a bar which, while it shall possess the maximum of strength, shall be of the lightest form and shall offer the least resistance to the passage of air to the fuel burning 15 thereon.

My invention consists in forming the bar as an open arch, the upper portion of which shall be straight and flat to receive the fuel, and of a thickness equal to or less than the air-space 20 between adjacent bars, and the lower portion of which shall be of an inverted-arch form, the ends curving up to projections which rest upon the bearing-bars to support the grates. The lower portion of the bar is gradually tapered 25 or thinned toward the bottom to offer the least possible obstruction to the passage of air between adjacent bars.

In the accompanying drawings, Figure 1 represents, in elevation, my improved grate- 30 bar, and Fig. 2 is a vertical section on the line *z z.*

Similar letters of reference indicate similar parts.

A is the grate-bar, provided with projections

a a, which rest upon bearers *B B*. The bearers 35 rest upon the side walls of the furnace, and pass transversely under the grate-bars in the usual manner. *A'* is the arched opening, with fillets at *a' a'*. The arched opening, through the web of the bar removes the metal from the 40 center and transfers it to the ends *A² A²*, whereby, for a given weight of iron employed, the bar is made much stronger than it would ordinarily be when constructed of the usual 45 form.

I am aware that perforated grate-bars are not new, and that a grate-bar having elongated and also triangular openings on opposite sides of a central sustaining-post is not 50 new, and such constructions are hereby dis- claimed.

Having described my invention, what I claim is—

The grate-bar herein described, formed with the downward-tapering web *A²*, extending the 55 length of said bar and terminating in end supports, *a*, said tapering web being formed at its center with the single arched opening *A'*, the base portion of the arched opening being formed in a straight plane, all constructed as shown, 60 and for the purpose set forth.

In testimony whereof I have signed my name to the foregoing specification in the presence of two subscribing witnesses.

CHARLES W. WITHENBURY.
